UNITED STATES PATENT OFFICE.

JOHN J. HESS, OF SEATTLE, AND NELS JOHNSON, OF SPOKANE, WASHINGTON.

RAIL TIE PLATE.

Application filed May 4, 1922. Serial No. 558,352.

To all whom it may concern:

Be it known that we, JOHN J. HESS and NELS JOHNSON, citizens of the United States, residing, respectively, at Seattle and Spokane, in the counties of King and Spokane, respectively, and State of Washington, have invented certain new and useful Improvements in Rail Tie Plates; and we do declare the following to be a full, clear, and exact 10 description of the invention, such as will enable others skilled in the art to which it appertains to make and use the same.

This invention relates to an improved tie plate having anti-creeping or rail locking 15 means associated therewith.

The principal object of the invention is to generally improve upon devices of this class by producing one which is practical, strong and durable, inexpensive to both the manufacturer and the user, effective in use and such that the locking action can be varied from time to time to compensate the wear of the parts of the device.

More specifically, it is another object of 25 the invention to devise a tie plate and rail lock embodying a conventional type of plate on which a locking lever is pivoted, this lever having its inner end disposed to engage the adjacent edge of the base flange of the 30 rail, and there being means cooperative with the outer or free end of the lever to hold it in the various locking positions to which it has been moved.

It is a feature of the invention to design 35 the locking lever so that it can be moved in either of two directions to prevent creeping of the rail in either of these directions.

Other objects and advantages of the invention will be apparent during the course 40 of the following description.

In the accompanying drawings forming a part of this specification and in which like numerals are employed to designate like parts throughout the same:

45 Figure 1 is top plan view of a tie-plate and rail lock constructed in accordance with this invention, the same being shown in use.

Figure 2 is an end elevational view partly in section.

50 Figure 3 is a top plan of the locking lever.

Figure 4 is a section on the line 4-4 of Figure 3.

For the purpose of illustration, the drawings show a rail R extending transversely 55 across a tie T.

The invention resides in the employment of a suitably designed tie-plate 1 having a rib extending across its upper face adjacent one end and formed with a plurality of openings to accommodate the fastening 60 spikes 3. On the opposite side of the rail, the plate is also formed with a screw threaded hole 4 into which the lower end of a shouldered pivot bolt 5 extends. This bolt 5 serves as a fulcrum for a locking lever 6 65 formed at its inner end with a cam head 7 to engage the adjacent edge of the base flange of the rail. At its outer or free end, the lever is formed with an opening 8 through which the shank of another spike 9 is designed to pass. It is to be noted that this opening is somewhat larger than the spike 70 to permit limited movement of the outer end of the lever after the spike has been driven.

From the foregoing description it is obvious that if the device is properly proportioned to accommodate a certain width of rail base, the cam head of the locking lever will be in locking engagement with base flange of the rail when the lever is disposed at a 75 substantially right angular position such as shown in dotted lines in Figure 1. As however the grip of the cam on the rail is not sufficient when the lever is in this position, it must be swung on its pivot to one side or the other as indicated by full lines to obtain the proper locking action. It is of course necessary for the lever to be in this position before the retaining spike 9 is driven into the tie. Even after the spike is in place, there 80 is still a slight movement of the lever permitted. Hence in case the rail tends to creep in the direction of the arrow a more effective locking grip will be automatically obtained. In Figure 1 of the drawings we 85 have shown the clearance of the bolt opening at the outer end of the lever in its final position. That is, it is to be assumed that the spike has been driven and that the clearance

was previously on the opposite side thereof 100 and that the rail has moved longitudinally in the direction of the arrow to bind the edge of the opening tightly against the shank of the spike. If the rail has a tendency to creep in an opposite direction, the lever 105 must be swung over to the opposite side of its right angular position. Hence, the device is capable of preventing creeping of the rail in either direction. It is also to be noted that in the event the cam head should 110

become worn to an extent to permit slippage of the rail, this can be taken care of by pulling the spike 9 and moving the lever over further toward the rail and replacing the 5 spike to maintain it in this new position.

By carefully considering the description in connection with the drawings, persons familiar with devices of this class will doubtless be able to obtain a clear understanding 10 of the invention. Therefore, a more lengthy and detailed description is deemed unnecessary.

Since probably the best results may be obtained with the construction and arrangement 15 herein shown and described, this is taken as the preferred embodiment of the invention. However, we wish it to be understood that minor changes coming within the scope of the invention as claimed may be 20 resorted to if desired.

We claim:

A device of the class described comprising a tie plate formed with a screw threaded opening on one side of the base flange of a rail, a bolt threaded into said opening, a 25 locking lever pivotally connected to said plate by said bolt, said locking lever being formed at its pivoted end with a cam head designed to frictionally grip the adjacent edge of the base flange of the rail, said lever being formed at its opposite end with an 30 opening, said opening being designed to permit passage therethrough of a retaining spike or the like to maintain the lever in various set positions. 35

In testimony whereof we have hereunto set our hands.

JOHN J. HESS.
NELS JOHNSON.
